SYRINGE

Richard E. Gross, Oakland, Calif.

Application May 22, 1939, Serial No. 274,993

1 Claim. (Cl. 128—266)

This invention relates to devices for injecting fluent materials into cavities and has particular reference to such a device for injecting materials in powdered form.

5 It is an object of the invention to provide a syringe which may be produced so economically that the major portion of the device which enters the cavity may be discarded after being used but once without incurring material loss to the 10 user.

Another object of the invention is to provide a syringe in which a component part thereof serves as a package in which correct doses of material to be applied may be dispensed.

15 The invention possesses other objects and features of advantage, some of which, together with the foregoing, will be specifically set forth in the detailed description of the invention hereunto annexed. It is to be understood that the invention is not to be limited to the particular species 20 thereof herein shown and described as various other embodiments thereof may be employed within the scope of the appended claim.

Referring to the drawing:

25 Figure 1 is a side elevational view, partly in vertical section, of the syringe tube showing it used as a dispensing package.

Figure 2 is a side elevational view, partly in vertical section and to a reduced scale, of the 30 complete syringe ready for use showing the tube connected with the fluid pressure generator.

Figure 3 is a view similar to Figure 2 showing a modified form of the invention.

In detail, the invention comprises a short 35 length of tubing 3, preferably constructed of superposed strips of paper or other such material, helically wound on a suitable mandrel. Within the tube is placed a measured charge of dry powdered material 4 and caps 6, which are 40 preferably constructed of gelatin or Celluloid, are forced over each end of the tube so as to retain the material 4 therein. In order to protect the material 4, which may be soluble, from coming in contact with moisture, the tube 45 3 is preferably impregnated with a waterproofing compound such as paraffin. The above described combination of elements forms a capsule or package in which the powder 4, pre-apportioned in correctly measured doses depending upon what use the powder is to be put to, may be sold. It is convenient to pack a quantity, for example a dozen, of these capsules in a box or other such container and sell them as a unit together with a suitable pressure generator 50 55 such as the rubber bulb 7 shown in Figure 2.

In using the syringe, the caps 6 are removed from both ends of the tube 3 and the slender spout 8 of the pressure generator is inserted into frictional engagement with one end of the tube. The opposite end of the tube is then inserted 5 into the cavity or opening into which the powder 4 is to be injected and the bulb 7 is suddenly and forcibly collapsed by the hand of the user. This will cause a blast of compressed air to flow out of the central bore 9 of the spout 8 and 10 through the tube, carrying with it the powder contained in the tube. It has been found that a single blast of air is sufficient to substantially completely evacuate of powder a tube having an internal diameter of $\frac{1}{16}$ of an inch and a length 15 of about four inches. It is quite important that the powder 4 be not of such fine mesh that when it packs in the tube under the action of vibration or shocks imposed on the tube in handling, it will be impervious to the passage of air there- 20 through since this condition will prevent the powder being quickly and easily blown from the tube.

In Figure 3 I have shown a variant form of my invention. In this construction, the tube 11, 25 which contains the measured charge of powder 12, is crimped at its discharge end to provide a restricted opening 13 through which the powder is blown and which causes the discharge blast to assume an outwardly diverging conical 30 form. The usual cap 6 is provided engaging and for closing the discharge end of the tube. The opposite end of the tube is provided with a cup-shaped piston 14, which may be constructed of pressed paper or similar inexpensive material, 35 having a peripheral flange 16 which is slightly less in diameter than the internal diameter of the tube and a tubular collar 17 is pressed into the end of the tube and engages the piston 14. It will be seen that the piston, engaging the col- 40 lar 17, forms a closure for the end of the tube which serves to retain the powder 12 therein. Thus the structure shown in Figure 3, less the rubber bulb 7, forms the package in which the powder is sold. When it is desired to inject the 45 powder, the spout 8 of the bulb is forced into the bore of the collar 17, the cap 13 is removed from the opposite end of the tube, and the tube is inserted into the cavity. The bulb 7 is then forcibly squeezed which will cause a blast of air 50 to flow along the tube driving the piston 14 before it. Due to the fact that the piston flange 16 is smaller in diameter than the tube bore, quantities of air will flow past the piston and will stir up and carry quantities of the powder 55

with it through the discharge end of the tube. It will be seen that when the piston has reached the discharge end of the tube, all of the powder will have been pushed from the tube and the crimped portions of the tube surrounding the aperture 13 will prevent the piston from passing out of the tube bore into the cavity along with the powder.

I claim:

- 10 A syringe comprising, in combination, a tubular dispensing package containing a measured quantity of powdered material, a removable cap closing one end of said tube, an apertured collar

pressed into the opposite end of said tubular package, a hollow cylindrical piston in said tubular package, movable longitudinally thereof and having a peripheral flange of lesser diameter than the inner diameter of said tubular package 5 which engages an end of said collar so as to close the said opposite end of the tubular package, and a hollow rubber bulb having a spout provided with a discharge orifice, said spout being insertible, in frictional engagement, into 10 said collar at said opposite end of the tube.

RICHARD E. GROSS.
